US0D1064742S

(12) United States Design Patent (10) Patent No.: US D1,064,742 S
(45) Date of Patent:  Mar. 4, 2025

(54) WATER BOTTLE

(71) Applicant: Zhejiang Fullstar Houseware Co., Ltd., Taizhou (CN)

(72) Inventor: Congqiang Lu, Taizhou (CN)

() Term: 15 Years

(21) Appl. No.: 35/518,945

(22) Filed: Jul. 28, 2023

(80) Hague Agreement Data

Int. Filing Date: Jul. 28, 2023

Int. Reg. No.: DM/232758

Int. Reg. Date: Jul. 28, 2023

Int. Reg. Pub. Date: Nov. 10, 2023

(51) LOC (15) Cl. 07-01

(52) U.S. Cl.

USPC D7/510; D9/532

(58) Field of Classification Search

USPC D7/507, 509-511, 533, 536, 543, 300.1, D7/300.2, 619.1, 391, 392.1, 396.1, D7/396.2, 629, 900; D3/202; D9/503, D9/435

CPC A63F 2009/0058; A47G 19/2205; A47G 21/18; A47J 41/00; B65D 1/00

See application file for complete search history.

Assistant Examiner — Tia Ruth-Renee Polidori

(57) CLAIM

The ornamental design for a water bottle as shown and described.

DESCRIPTION

1. Water bottle

1.1: Perspective

1.2: Perspective

1.3: Front

1.4: Back

1.5: Left

1.6: Right

1.7: Top

1.8: Bottom

1.9: Perspective

The portions of the water bottle shown in broken lines form no part of the claimed design.

1 Claim, 9 Drawing Sheets
